UNITED STATES PATENT OFFICE.

ADOLPH DIETSCHE, OF FOREST HILLS, NEW YORK, ASSIGNOR TO AMERICAN LITHOGRAPHIC COMPANY, OF NEW YORK, N. Y., A CORPORATION OF NEW YORK.

ARTICLE-DISPLAY RETAINER.

1,333,102.

Specification of Letters Patent.

Patented Mar. 9, 1920.

Application filed July 2, 1917. Serial No. 178,058.

To all whom it may concern:

Be it known that I, ADOLPH DIETSCHE, a citizen of the United States, and a resident of Forest Hills, in the county of Queens and State of New York, have invented certain new and useful Improvements in Article-Display Retainers, of which the following is a specification.

This invention relates to article display retainers, such for instance as are employed for surrounding at its base and preserving in predetermined conformation a pile of small articles, such as oranges or the like, resting upon a horizontal support, and has for its object to provide a device of the class specified simple in construction and economical of manufacture, efficient in use, and requiring but small space in shipping.

With these ends in view my improvements comprise in their preferred embodiment a strip of cardboard or other suitable sheet material having interlocking means at its ends whereby a single strip may, when of sufficient length, be assembled into a circular band. Or, when strips of comparatively short length are used, several of such strips may be thus assembled together in circular form.

In the accompanying drawing—

Figure 1 is a perspective view illustrating my improved device as comprised of several strips assembled together ready for use. Fig. 2 is a front elevation of an individual strip. Figs. 3 to 8 inclusive are a series of pairs of fragmentary front elevations and plan views respectively, illustrating several steps in assembling the interlocking means. Figs. 9, 10 and 11 are three fragmentary front elevations illustrating alternate constructions respectively of one portion of the interlocking means. Fig. 1 is to one scale, and Figs. 2 to 11 inclusive are to another and larger scale.

In a device of the character specified it is highly desirable that it be adjustable as to diameter of band formed when assembled and thus readily adaptable to a variety of conditions in use. This is greatly facilitated by having the individual strip of comparatively short length. Also the short length strip tends to economy in cost of manufacture, as frequently the material for

said short length strip may be obtained from waste cuttings incident to other lines of manufacture.

55

Directing attention now to the drawing, strip 2 therein is shown provided at one end with a lengthwise extending neck 3 having a head 4 provided with opposite, lateral, outwardly extending ears 5, 6. Near the other end of said strip 2, a transverse opening 7 is provided for the reception therethrough of said head 4. Opposite portions 8, 9 of longitudinal edge 10 of opening 7 are adapted for interlocking engagement with ears 5, 6 respectively, of said head 4. Said opposite portions 8 and 9 converge toward the adjacent end 11 of strip 2 and thus have an angular relation respectively to ears 5 and 6, which causes ready and effective interlocking of the parts when in operative positions. The other longitudinal edge, 12, of opening 7 is of tongue-like formation, the action of which will be described later herein. Said head 4 has a maximum width from ear to ear slightly less than the length transversely of the strip of opening 7.

I preferably form transverse opening 7 as illustrated in Figs. 1 to 8 inclusive, but modifications of said opening, as shown in Figs. 9, 10 and 11 are sometimes found desirable. In Figs. 9 and 11 the longitudinal edge 12 of opening 7 is of straight conformation so that the tongue effect of the other figures is absent.

85

The operation of assembling my improved device is as follows: When the device is comprised of one long strip, said strip is first bent into a band of approximately circular form, when end 11 is sprung inwardly and head 4 passed thereover, under tongue 12 and entered into opening 7, as shown in Figs. 3 and 4. Head 4 now continuing in the same direction until, having passed entirely through said opening 7, ears 5 and 6 snap into the positions of Figs. 5 and 6, due to the pressure of tongue 12 against that portion of the strip lying adjacent said head, and well within the inner surfaces of said opposite portions 8 and 9 respectively. The band then being distended and head 4 moved in the opposite direction, ears 5 and 6 thereof pass into interlocking engagement with said opposite portions 8 and 9 respec-

100

tively and said head comes to rest, through the intersections of neck 3 and ears 5 and 6 respectively, seating against edge 10 of opening 7, as shown in Figs. 7 and 8. This 5 action of head 4 seating against edge 10 of opening 7 also draws the overlapping portions of the strip into alinement.

When the device is comprised of several 10 comparatively short strips the assembling is the same with the exception that head 4 of one strip is passed over end 11 of another strip and entered into transverse opening 7 thereof, one strip with another, until the circular band is completed.

15 In assembling where the modifications of Figs. 9 and 11 are used, the tongue-like formation of longitudinal edge 12 of transverse opening 7 being absent, it is necessary for the operator to place ears 5 and 6 in interlocking positions entirely by hand.

I claim:

An article display retainer comprising a strip of material, a head formed at one end of said strip and having outwardly directed ears, the other end of said strip having a 25 curved transverse opening therein of greater length than said ears whereby said head is directly insertible within said opening with the ears engaging one side wall of the curved opening for retention and being 30 spaced from the ends of the slot.

Signed at New York, borough of Manhattan, in the county of New York and State of New York, this 29th day of June, 1917, before two subscribing witnesses.

ADOLPH DIETSCHÉ.
